UNITED STATES PATENT OFFICE.

EDMUND S. SPINNEY, OF ABINGTON, MASSACHUSETTS, ASSIGNOR TO JEREMIAH FITZPATRICK, OF BRAINTREE, MASSACHUSETTS, AND CHARLES H. FITZPATRICK, OF NORTH ABINGTON, MASSACHUSETTS.

MACHINE FOR SETTING EYELETS, RIVETS, AND THE LIKE.

Application filed March 26, 1924. Serial No. 701,978.

To all whom it may concern:

Be it known that I, EDMUND S. SPINNEY, of Abington, in the county of Plymouth and State of Massachusetts, a citizen of the United States, have invented a new and useful Improvement in Machines for Setting Eyelets, Rivets, and the like, of which the following is a full, clear, and exact description, reference being had to the accompanying drawings, forming a part of this specification, in explaining its nature.

The present invention relates to a machine for setting eyelets, rivets and the like.

The object of the invention is to provide a machine of the above character which is simple and economic in its structure, efficient in its operation and will maintain its efficiency and not easily get out of order or wear out.

The invention can best be seen and understood in the light of the drawings where an embodiment thereof is shown and in which—

Figure 1 is a side elevation of the machine.

Fig. 2 is a plan.

Fig. 3 is a section taken on the line 3—3 of Fig. 2.

Fig. 4 is a section taken on the line 4—4 of Fig. 2.

Fig. 5 is a section taken on the line 5—5 of Fig. 4.

Figs. 6 and 7, respectively, are side elevations of that part of the machine carrying the punch and setting mechanism later to be referred to, the figures showing different operative positions assumed by the respective mechanisms in the operation of the machine.

Referring to the drawings:

1 represents the frame of the machine. The frame is provided with an under extending part 2 and overhanging the same an extending part 3 with space 4 between the two parts. Mounted within the space 4 is a work table 5, having within it an opening 6, arranged preferably in an inclined position as shown which is supported by a bracket 7 secured to the extension 2 of the frame.

Mounted upon the frame extensions 2 and 3 are punch and setting mechanisms. The punch mechanism comprises a punch proper

8 (see Figs. 6 and 7) preferably tubular in form secured to the end of a carrier bar 9 mounted to slide within a way 10 in the part 3 of the frame. Cooperating with the punch 8 is a member or anvil 11 secured to the end of a carrier bar 12 mounted to slide within a way 13 in the part 2 of the frame. The anvil has a top surface 14 having the same inclination as the table in order that it may assist in the support of the work on the table during the punching operation, as will later be more fully explained. The anvil 15 is also provided with a receding centre or core 15 which also assists in the support of the work during the punching operation and by its permitted recession into the anvil and carrier therefor permits of the punch 8 entering the anvil after passing through the work when the respective punch members are brought into an engaging position with relation to the work.

The setting mechanism comprises a member 16 having an annular clenching surface 17 and extending from this surface a central tubular projection 18 which enters the centre of the eyelet during the setting operation. The member 16 is borne by a carrier 19 mounted to slide within a way 20 in the part 3 of the frame.

Arranged in opposition to and cooperating with the setting member 16 is a setting member 21 having an annular clenching surface 22 and a spring finger 23 adapted to receive eyelets from an automatic feed during the operation of the machine, as will later be explained. During the setting operation the spring finger 23 recedes into the setting member 21 and carrier therefor as the clenching surfaces 17 and 22 of the respective setting members are brought into engagement with the eyelet or work and the projection 18 of the member 16 enters the centre of the eyelet. The setting member 21 is borne by a carrier 24 slidable within a way 25 in the part 2 of the frame.

The cooperating members and carriers therefor of both the punch and setting mechanisms are mounted in opposition to one another above and below the table and are slidable upon the frame with a reciprocating motion toward and away from one another and the opening in the table into and out of engaging positions. The members of

- the respective mechanisms preferably all lie in the same plane, which plane is a right angle to the face of the table. The respective mechanisms are also arranged in positions angular to one another and operate along lines having relatively such acute angularity that as the mechanisms are successively operated they will engage the work relatively to the opening in the table at a substantially common point, the punch mechanism engaging the work when the setting mechanism is in its disengaged, and preferably extreme disengaged, position, and vice versa.
- 15 The means for operating and assisting in the support of the punch and setting mechanisms is also such that the two mechanisms will engage the work in such relation to the opening in the table and work laid thereon covering said opening, that the work will not be elevated above the opening or depressed into the opening during the punching and setting operations. In other words, during the punching operation the member 11 of the punch or anvil will be elevated to a position where its top surface 14 will lie substantially within the plane of the top surface of the table and will accordingly support the work immediately adjacent the point where the hole is made in it as the other cooperating punch member 8 or punch proper is passed through the work. In a similar manner during the setting operation the member 21 of the setting mechanism will be brought up into a position where its clenching surface 22 will lie substantially within the plane of the top surface of the table as the clenching surface 17 of the other cooperating member is brought down into engagement with the eyelet for upsetting it. The under clenching surface 22 of the setting mechanism will accordingly assist in the support of the eyelet during the setting operation.
- 45 It will also be observed that the respective members of the setting mechanism operate along a line or path substantially at a right angle to the plane of the table in order that the respective clenching surfaces of the setting mechanism may squarely engage the eyelet for effecting a proper upsetting thereof in relation to the work. Such disposition of the setting mechanism necessitates that the punch operate at a slight angle with relation to the work with a tendency to make an inclined opening through the work, but such inclination is negligible in practice.
- Reference will now be made to the means for operating the punch and setting mechanisms:
- 65 Both mechanisms are operated directly by a pair of levers 30 and 31. These levers are mounted on a shaft 32 which has bearing to turn on the frame just back of the opening 4 between the parts 2 and 3 of the

frame. The lever 30 is provided with a hub 33 by which it is mounted to turn freely on the shaft 32. The lever 31 is provided with a hub 34 by which it is mounted on the shaft 32 and is secured thereto by a set screw 35 70 by which the lever 31 is secured to the shaft to turn therewith.

The two levers 30 and 31 are simultaneously actuated by a crank shaft 36 through a connecting crank 37. The crank shaft 36 75 is mounted to turn on the frame of the machine and is turned by a power-driven pulley as will later be explained. The levers 30 and 31 besides operating the members of the punch and setting mechanisms assist also 80 in the positioning of these members.

The general form, arrangement and operation of the levers are as follows: The lever 30 forward of the shaft 32, on which it is mounted to turn, is bifurcated to provide 85 arms 39 and 40 respectively, the arm 39 having a slot 39' therein and the arm 40 a slot 40' therein. That portion of the lever extending to the rear of the shaft 32 comprises an arm 41 having within it a slot 41'. 90 It is also to be noted that the lever is provided with an offset 42 by which the arm 41 thereof is slightly offset from the plane of the arms 39 and 40 to permit of the insertion of one of the crank arms of the crank 95 mechanism later to be referred to.

The lever 31 in the part thereof lying forward of the shaft 32 to which the lever is secured is bifurcated to provide arms 43 and 44 respectively. The arm 43 has in it a slot 43' and the arm 44 has in it a slot 44'. That portion of the lever lying to the rear of the shaft 32 comprises an arm 45 having in it a slot 45'. The slotted arms to the bifurcated portions of the respective levers extend by the sides of the parts 2 and 3 of the frame in which lie the various movable carriers for the punch and setting mechanisms. Slots 47 are formed in the frame parts 2 and 3 in the sides of these parts facing the projecting arms of the respective levers. These slots extend in directions parallel with the various carriers of the punch and setting mechanisms and lead respectively into the ways in which the carriers reciprocate. Secured to each one of the carriers is a stud 48 extending laterally therefrom through the slot 47 adjacent the carrier, and thence extending to be contained in one of the slotted arms of the two levers 30 and 31. In this connection it will be observed that the stud 48 on the carrier 9 for the punch member 8 is contained within the slot 43' in the arm 43 of the lever 31, and the stud 48 on the carrier 12 for the punch member or anvil 11 110 is contained within the slot 40' in the arm 40 of the lever 30. On the other hand, the stud 48 on the carrier 19 of the setting member 16 is contained within the slot 39' in the arm 39 of the lever 30, while the stud 48 on 115

120 the carrier 24 for the setting member 21 is contained within the slot 45' in the arm 45 of the lever 31. In this connection it will be observed that the stud 48 on the carrier 24 for the setting member 21 is contained within the slot 45' in the arm 45 of the lever 31, while the stud 48 on the carrier 19 for the setting member 21 is contained within the slot 39' in the arm 39 of the lever 30, while the stud 48 on 125 130

the carrier 24 of the setting member 21 is contained within the slot 44' in the arm 44 of the lever 31. Thus arranged the various carriers of the respective punch and setting mechanisms and members carried thereby will be properly actuated as the levers 30 and 31 are turned in reverse directions.

As previously noted, the levers 30 and 31 are actuated simultaneously by a crank shaft 36 through a connecting crank 37. The crank 37 is a double-acting crank. It has a crank arm 51 fixed to the end of the crank shaft 36. This arm bears upon its end a laterally-extending crank pin 52 which is contained to lie within the slot 45' in the arm 45 of the lever 31. The crank pin 52 has secured to it a crank arm 53 which lies between the arms 41 and 45 of the respective levers 30 and 31 and extends in a direction reverse to the direction of the crank arm 51 through the axis of the crank shaft, if such axis were extended, the extension of the crank arm 53 beyond the axis of the crank shaft being a distance substantially equal to the length of the crank arm 51. The crank arm 53 bears upon its end a laterally-extending crank pin 54 which is contained within the slot 41' in the arm 41 of the lever 30.

The normal position of the parts is substantially that shown in Figs. 1 and 2. The levers 30 and 31 will be turned to a position where they will hold the respective members of the punch and setting mechanism in disengaged position. The arms 41 and 45 of the respective levers 30 and 31 together with the slots 41' and 45' in these arms will occupy a horizontal position in substantial parallel alignment with one another and the respective crank arms 51 and 53 of the crank will have a similar horizontal disposition, their arrangement also being such that the crank pin 52 will be located at the outer end of the slot 45' in the arm 45 of the lever 31 and the crank pin 54 will be located at the inner end of the slot 41' in the arm 41 of the lever 30.

With the parts thus disposed and arranged, the turning of the crank shaft 36 a single revolution in a clockwise direction as observed from the side of the machine shown in Fig. 1 will cause the various parts to function as follows: As the crank shaft is turned the crank arm 51 will move the crank pin 52 inwardly along the slot 45' in the arm 45 of the lever 31 and will elevate this arm and, by the rocking of the lever, depress its arms 43 and 44, whereupon the punch member 8 of the punch mechanism actuated by the arm 43 of the lever will be moved to an engaging position, while the member 21 of the setting mechanism will be moved by the arm 44 of the lever into a more retracted position. Simultaneously with this operation the crank arm 53 will move the crank pin 54 outwardly along the slot 41' in the arm 41 of the lever 30 and will depress this

arm and, by the rocking of the lever, elevate its arms 39 and 40, whereupon the punch member or anvil 11 of the punch mechanism will be moved by the arm 40 of the lever 30 into an engaging position and the member 16 of the setting mechanism will be moved by the arm 39 of lever 30 into a more retracted or disengaged position.

The extreme engaging position of the punch member 8 will be reached when the crank shaft has been turned substantially one quarter of a complete turn and the crank arm 51 is in a position at substantially right angles to the slot 45' in which the crank pin 52 is working. As the movement of the crank shaft continues up to substantially a one half complete turn the continued movement of the crank arm 51 will move the crank pin 52 further inwardly along the slot 45' in which it is working and thereupon the rocking movement of the lever 31 will be reversed and the punch member 8 of the punch mechanism and the member 21 of the setting mechanism will be moved back to their normal disengaged positions.

The extreme engaging position of the punch member or anvil 11 will be reached when the crank shaft has been turned substantially one quarter of a complete turn and the crank arm 53 is in a position at substantially right angles to the slot 41' along which the crank pin 54 is working. As the movement of the crank shaft continues up to substantially a one half complete turn the continued movement of the crank arm 53 will move the crank pin 54 further outward along the slot 41' in which it is working and thereupon the rocking movement of the lever 30 will be reversed and the punch member or anvil 11 of the punch mechanism and the member 16 of the setting mechanism will be returned to their normal disengaged positions.

During the operation just described the punch member or anvil 11 will have been moved to its full engaging position with the face 14 of the anvil substantially flush with the top surface of the table just prior to but practically simultaneously with the time when the punch member 8 has been moved to a proper engaging position for making a hole in the work to receive the eyelet. When the punch member or anvil 11 has reached its full engaging position and the punch member 8 has functioned as aforesaid the member will be moved away from its engaging position, but the engagement of the member 8 will continue until the crank arm 51 has been moved to a position at substantially right angles to the slot 45' in which it is working. By the recession of the anvil 11 its surface 14 will move below the face of the table on which the work is resting and consequently the work will no longer be supported at the point of the opening in

the table by the top surface 14 of the anvil at the very time when the member 8 of the punch is continuing to operate. Consequently the work will be slightly depressed 5 by the punch member 8 into said opening. This is undesirable and is obviated by preventing a continued movement of the lever 31 operating the punch member 8 after this member has reached its proper engaging 10 position for making a hole in the work. It is accomplished by making a slight offset 60 in the arm 45 of the lever 31 along the top surface of the slot 45' therein. This offset is so positioned that the crank pin 52 working inwardly along the slot 45' will, after the crank arm 51 has moved the punch member 8 to a proper engaging position, reach the offset and thereupon will cause a lag 15 in the operation of the lever 31 and consequently the engagement of the punch member 8 with the work will no longer be continued after the depression of the anvil 11 has commenced. After the crank pin 52 has passed the offset then the rocking movement 20 of the lever 13 will be continued and both levers will return the members of the punch and setting mechanisms to their initial disengaged positions.

Thus far the operation attending a substantially one half complete turn of the crank shaft has been explained. The crank pin 52 will then be occupying its extreme inward position within the slot 45' in which it is working and the crank pin 54 its extreme outward position in the slot 41'. As the movement of the crank shaft continues the crank pin 52 through the operation of the crank arm 51 will work outward within the slot 45' in the arm 45 of the lever 31 depressing this arm and, by the rocking of the lever, elevating its arms 43 and 44. Thereupon the punch member 8, actuated by the arm 43 of the lever, will be moved into a more disengaged position, while the member 21 of the setting mechanism will be moved by the arm 44 of the lever into an engaging position. Simultaneously with this operation the operation of the crank arm 53 will move the crank pin 54 inwardly 45 along the slot 41' in the arm 41 of the lever 30 and will accordingly elevate this arm and, by the rocking of the lever, depress its arms 39 and 40. Thereupon the punch member or anvil 11 will be moved by the arm 40 50 of the lever 30 into a more disengaged position and the member 16 of the setting mechanism will be moved by the arm 39 of the lever 30 into an engaging position.

The full engaging position of the setting member 21 will be reached when the crank shaft has been turned substantially a further one quarter turn beyond its half turn and the crank arm 51 is in a position at substantially right angles to the slot 45' in which 55 the crank pin 52 is working. As the move-

ment of the crank shaft continues up to its complete turn the continued movement of the crank arm 51 will move the crank pin 52 further outward along the slot 45' in which it is working and thereupon the rocking movement of the lever 31 will be reversed and the member 21 of the setting mechanism and punch member 8 of the punch mechanism will be moved back to their normal disengaged positions. 70

The extreme engaging position of the setting member 16 will be reached when the crank arm 53 is in a position at substantially right angles to the slot 41' in the arm 41 of the lever 30 in which the crank pin 54 is working. As the movement of the crank shaft continues up to the time of its complete turn the continued movement of the crank arm 53 will move the crank pin 54 further inward along the slot 41' in which it is working and thereupon the rocking movement of the lever 30 will be reversed and the member 16 of the setting mechanism and punch member or anvil 11 of the punch mechanism will be returned to their 75 normal disengaged positions. 80

During the operation just described the setting member 21 will have been moved to its full and proper engaging position with the clenching face 22 of this member substantially flush with the top surface of the table just prior to but practically simultaneously with the time when the said member 16 has been moved to a proper engaging position for upsetting the eyelet. When the setting member 21 has reached its full proper engaging position and the setting member 16 has reached an engaging position to properly cooperate therewith for upsetting the eyelet then the member 21 will be moved away from its engaging position, but the member 16 will continue to be moved in the direction of a more extreme position of engagement until the crank arm 53 has been moved to a position at substantially right angles to the slot 41' in the arm 45 in which it is working. By the recession of the setting member 21 its clenching surface 22 will move below the face of the table on which the work is resting and consequently the work will no longer be supported at the point of the opening in the table at the very time when the setting member 16 is continuing to operate. In other words, the setting member 16 will follow the setting member 21 as it recedes and consequently the work will be slightly depressed into the opening in the table. This is undesirable and is obviated by preventing a continued movement of the lever 30 for operating the setting member 16 after this member has reached a proper position to cooperate with the setting member 21 for upsetting the eyelet and before the member 21 has receded. It is accomplished by making a slight off- 85 90 95 100 105 110 115 120 125 130

set 61 in the arm 41 of the lever 30 along the top surface of the slot 41' therein. This offset is so positioned that the crank pin 54 working inwardly along the slot 41' will, 5 after the crank arm 53 has moved the setting member 16 to a proper engaging position, reach the offset and thereupon will cause a lag in the operation of the lever 30 and consequently the engagement of the setting member 16 with the work will no longer be continued after the depression of the setting member 21 has commenced. After the crank pin 54 has passed the offset then the rocking movement of the lever 30 will 10 be continued and both levers will return the members of the punch and setting mechanisms to their initial disengaged positions.

An automatic feed is provided for the purpose of feeding eyelets to the spring finger 23 of the setting mechanism in order that the finger may severally pick up the eyelets as they are fed to it and insert the eyelet picked up in the hole punched in the work after the functioning of the punch mechanism and preliminary to the action of the setting mechanism. To this end an automatic feeding device 65 of common type is employed having a hopper 66 and a feed chute 67 leading from the hopper, and from the end of which chute the eyelet is picked off in the usual manner by the spring finger 23 as the chute is reciprocated or oscillated to present the eyelet to the finger. In order to obtain a proper reciprocation or oscillation of the chute, it together with the hopper is mounted upon a sliding carrier 68 arranged alongside the frame and occupying an inclined position in relation thereto. The carrier has in it a slot 69 through which extends a bolt 70 passed through the frame and retained by a tightening nut 70'. The retention of the bolt is such that its head will draw against the side of the carrier and frictionally hold it in any position to which it may be moved within the range permitted by the slot 69. The carrier is otherwise slidably supported by an upwardly-extending arm 71 supported from off the upper end of a crank arm 72 on the end of the shaft 32 (on which the levers 30, 31 are mounted) by a pin 74 extending laterally from the arm 71 and contained within an inclined slot 75 in the upper end of the crank arm 72. Thus arranged the automatic feed will operate as follows: The normal position of the chute is one in which the end of the chute is away from the punch and setting mechanisms. As the levers 30 and 31 are turned for moving the members of the punch mechanism into engaging positions the shaft 32 will turn with the lever 31 and thereby through the crank arm 72, pin 74 and arm 71 move the sliding carrier 68 and feeding device with it in a forward direction 15 until the mouth of the chute 67 and eyelet

therein is substantially within the path of the spring finger 23 of the setting mechanism. According to the operation of the levers 30 and 31 previously described their next movement is a reverse movement for 70 moving the members of the punch and setting mechanisms back to their normal or disengaged positions and afterward moving the members of the setting mechanism into their engaging positions. During this first 75 movement or the movement for returning the members of the punch and setting mechanisms to their original disengaged positions the reverse movement of the shaft 32 will not disturb the chute as the pin 74 will 80 draw along the slot 75 in the crank arm 72. This condition remains until the lever 31 has elevated the finger 23 of the setting mechanism to a position where it will pick the eyelet off the end of the chute. The 85 crank arm 72 will then have been moved to a position where it will again be in engagement with the pin 74 then located at the forward end of the slot 75 in the crank arm and the then continuing reverse movement 90 of the shaft 32, attending the operation of the levers 30 and 31 for moving the members of the setting mechanism into an engaging position, will return the chute to its 95 normal disengaged position. Here it will remain until the members of the punch mechanism are again moved into an engaging position, for as the levers turn to return the members of the setting mechanism to their disengaged position the ensuing reverse turning of the shaft 32 will cause the crank arm 72 to draw over the pin 74 by reason of the slot 75 in the end of the arm and consequently will not disturb the position of the chute. All parts will then be occupying 100 their initial positions preparatory to the next ensuing operation of the machine. 105

In connection with the operation of the automatic feed it will be further explained that the hopper 66 of the feed mechanism is provided inside the hopper with the usual stirrer or brush (not shown) which turns or oscillates on a pin 77 mounted to turn in bearings on the top and bottom walls of the hopper. To this pin an arm 78 is fixedly secured and pivotally connecting with this arm is a link 79 loosely mounted on the end of the bolt 70 laterally extending from the side of the frame. As the feeding device including the hopper and chute are reciprocated during the operation of the machine the stirrer or brush inside the hopper will be agitated by the arrangement of the parts thus described. 115

The machine further embodies a clutch-forming mechanism having an automatic release whereby only a single complete turn or rotation is permitted the driving shaft 32 when the clutch is thrown in, the punching of the hole in the work, application of 120 125 130

the eyelet to the work and setting of the eyelet being completed during such one complete rotation of the driving shaft.

To this end the driving shaft is provided 5 with a pulley 80 mounted to turn loosely upon it and to which pulley power is applied in any suitable manner. The pulley 80 has on its inner side facing the frame an annular ring or flange 81 and projecting 10 laterally from this flange are a number of studs 82. Mounted upon the main shaft 32 alongside the pulley on the side thereof provided with the studs is a hub 84 which is fixed to the shaft. This hub has on one side 15 thereof a hub extension 84' with a slot 85 in it. In this slot, pivoted to the hub by a pin 86, is arranged a clutch member 87 extending outwardly from the hub extension in a direction radial to the main shaft and 20 movable into an engaging or disengaging position with relation to the pulley 80 and studs 82 carried by it. When in an engaging position the clutch member will be moved to a position where its side 87' will 25 bear against the annular flange on the pulley, the body of the clutch member then being interposed or lying within the path of the studs carried by the pulley as the pulley is rotated and consequently may be engaged 30 by any one of said studs as the pulley is turned. From this engaging position the clutch member is movable away from the annular flange on the pulley and out of the path of the studs thereon. It will also be 35 observed that the clutch member has such extension that the outer end 87² thereof will project beyond the outer face of the annular flange 81 on the pulley. The clutch member is yieldingly maintained in an engaging position by means of a spring 88 fixed to it and to the hub extension 84' on which the clutch member is mounted.

Mounted on a hub 89 arranged to turn upon a stud 90 fixed to the frame in a position beneath the clutch member 87 is an upwardly-extending clutch-controlling arm 92. This arm turns upon an axis parallel with the axis of the main shaft 32 and the upper end of the arm, as the arm is pivotally 45 turned, moves in a general direction toward or away from the shaft 32 and thereby into different operative positions with relation to the clutch member 87. The upper end of the arm presents an outwardly turned portion 93 which when the arm is moved inwardly in the direction of the main shaft is adapted to bear against the periphery of the annular flange 81 on the pulley. This portion of the arm having such bearing is 55 provided with an inclined side 94 which, when the end of the arm is bearing against the annular flange on the pulley, lies within the plane of the studs on the pulley and just outside the path described by the studs when 60 the pulley is rotated. The upper end of the

arm has also a face surface 95 on the side thereof facing the main shaft and also presents a side edge surface 96 on the side facing the frame of the machine and a stop 97. Attached to the hub 89 on which the clutch-controlling arm 92 is mounted is a lever 98. To the outer end of this lever is secured a spring 99 attached to the frame of the machine, the arrangement being such that the draft of the spring upon the lever will normally hold the arm 92 in its inturned position from which position the arm may be released by draft upon a link 100 connected to the opposing inner arm of the lever 98, the draft being applied by any suitable means, preferably by a connected foot pedal (not shown).

The operation of the clutch mechanism is as follows: The normal position of the arm 92 is its inturned position with the upper 5 end 93 of the arm bearing against the annular flange 81 on the pulley. When thus positioned the clutch member will have bearing against the side 96 of the arm resting against the stop 97 and thereby be maintained in a disengaging position with relation to the studs 82 borne by the pulley, and accordingly the pulley when rotated will simply idle upon the shaft 32.

Assuming now that the clutch-controlling arm is released outwardly by draft on the link 100, thereupon by the turning of lever 98 the arm 92 moved outwardly will release the clutch member 87 into an engaging position with bearing against the side 10 of the annular flange on the pulley and disposed within the path of the studs 82 as the pulley is rotated. When thus released into an engaging position the face 95 of the arm will bear against the outer end 87² of the clutch member and the arm will thereby be maintained in an outturned position. Immediately upon the clutch member entering the path of the studs 82 on the pulley it will be engaged by some one of the studs 105 and thereupon the pulley will, through the clutch member, turn the main shaft 32. As the shaft is turned the clutch member will be turned away from the clutch-controlling arm 92 and thereupon this arm will resume its normal inturned position. The rotation of the main shaft will continue until the clutch member has been brought around 110 to a position where the outer projecting end 87² thereof will engage the inclined surface 94 of the clutch-controlling arm. Immediately on contact with this surface the clutch member will ride thereon and be moved inwardly out of the path of the stud driving it and onto the side 96 of the arm where it will be maintained in a disengaged position resting against the stop 87 on the arm and the pulley then left to idle. The release of the clutch member is commensurate with a single turn or revolution 115

of the main shaft, the same operation being continued as the machine is successively operated.

In the general operation of the machine 5 it will be understood that the work is placed upon the table and maintained thereon in any suitable manner as by hand or otherwise. The clutch mechanism is then thrown in and the machine left to function without 10 more, it being entirely automatic after the once placing of the work and throwing in of the clutch, the clutch being thrown out at the completion of the operation.

Having thus fully described my invention, I claim and desire to secure by Letters Patent of the United States:

1. In a machine of the type specified, the combination comprising a punch mechanism having cooperating punch members, a setting mechanism having cooperating setting members, means for mounting said respective mechanisms in positions angular to one another whereby they may severally engage the work at a substantially common point, 25 and means for successively operating said respective mechanisms.

2. In a machine of the type specified, the combination comprising a punch mechanism having cooperating punch members, a setting mechanism having cooperating setting members, means for mounting said respective mechanisms whereby they may successively function along paths having an acute angularity to one another and meet at a point 35 common to both, and means for operating said mechanisms to function as aforesaid.

3. In a machine of the type specified, the combination comprising a punch mechanism having cooperating punch members, a setting mechanism having cooperating setting members, means for mounting the members of said respective mechanisms to lie all in the same plane and occupy positions angular to one another whereby the mechanisms 45 when successively operated will engage the work at a substantially common point, and means for successively operating said respective mechanisms.

4. In a machine of the type specified, the combination comprising a punch mechanism having cooperating punch members reciprocable respectively toward and away from one another, a setting mechanism having cooperating setting members reciprocable 55 respectively toward or away from one another, means for mounting the members of said respective mechanisms whereby they may be reciprocated into and out of engaging positions on lines angular to one another and engage the work at a substantially common point when occupying an engaging position, and means for reciprocating the members of said respective mechanisms to successively occupy their engaging positions.

5. In a machine of the type specified, the combination with the frame of the machine, of a work table having an opening in it, a punch mechanism having cooperating punch members, a setting mechanism having co- 70 operating setting members, means for mounting the members of said respective mechanisms to be movable along independent lines of travel toward and away from said opening in the table and to assume en- 75 gaging positions adjacent said opening at a point substantially within the plane of the top surface of said table, and means for successively operating said respective mechanisms.

6. In a machine of the type specified, the combination comprising a punch mechanism having separate members movable in reverse directions into and out of an engaging position, a setting mechanism having separate members movable in reverse directions into and out of an engaging position, means for mounting said members of said respective mechanisms to be movable as aforesaid along independent lines of travel and to have a substantially common engaging point 90 relatively to the work, means for successively operating said mechanisms, and means for automatically supplying eyelets to the said mechanisms.

7. In a machine of the type specified, the combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable on lines angular to one another, a set of levers in operative engagement with said members for successively operating them as the levers are rocked simultaneously in reverse directions, and means for operating said levers.

8. In a machine of the type specified, the combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable into and out of engagement on lines angular to one another, a set of levers, a mounting therefor, each of said levers having arms oppositely arranged and in operative engagement with the members of both the punch and setting mechanisms whereby said members may be successively operated in reverse directions as the levers are reversely turned, and means for operating said levers.

9. In a machine of the type specified, the

combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable on lines angular to one another, a set of levers in operative engagement with said members for successively operating them as the levers are rocked simultaneously in reverse directions, a power-driven shaft and a crank operated by the shaft having arms reversely turned and in operative engagement with said respective levers for simultaneously rocking the same in reverse directions as the shaft is turned.

10. In a machine of the type specified, the combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable on lines angular to one another, a set of levers in operative engagement with said members for successively operating them as the levers are rocked simultaneously in reverse directions, a shaft on which said levers are mounted and to which one of said levers is secured, an automatic feed adapted to cooperate with the setting mechanism, means whereby said automatic feed may be operated by said shaft to cooperate with said setting mechanism as aforesaid, and means for simultaneously operating said levers.

11. In a machine of the type specified, the combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable on lines angular to one another, a set of levers in operative engagement with said members for successively operating them as the levers are rocked simultaneously in reverse directions, means for simultaneously operating said levers, a shaft on which said levers are mounted to which

one of said levers is fixed, an automatic feed adapted and arranged to cooperate with the setting mechanism during the operation of the machine, a mounting for said feed, and means whereby said feed may be moved by said shaft in reverse directions with periods of dwell, substantially as described.

12. In a machine of the type specified, the combination of a punch mechanism having cooperating punch member movable in reverse directions into and out of engagement with one another, a setting mechanism having cooperating setting members movable in reverse directions into and out of engagement with one another, means for mounting said members of said respective mechanisms to be movable on lines angular to one another, a set of levers in operative engagement with said members for successively operating them as the levers are rocked simultaneously in reverse directions, a shaft on which said levers are mounted and to which one of said levers is secured, an automatic feed adapted to cooperate with said setting mechanism, a crank arm fixed to the shaft on which said levers are mounted, said crank arm having a slot in the end thereof, an arm connected to said feed and bearing a pin contained in the slot of said crank arm, means for otherwise assisting in the support of said feed, and means for simultaneously operating said levers.

13. In a machine of the type specified, the combination of a punch mechanism having cooperating punch members movable in reverse directions into and out of engagement with one another, a setting mechanism having cooperating setting members movable in reverse directions into and out of engagement with one another, means for mounting said members of said respective mechanisms to be movable on lines angular to one another, a power-driven shaft, a set of levers in operative engagement with said members for successively operating them as the levers are rocked simultaneously in reverse directions, means whereby said shaft will have operative engagement with said levers for simultaneously rocking the same as aforesaid during a single rotation of said shaft, and a releasable clutch mechanism controlling the operation of said shaft and permitting only of a single rotation thereof on the release of said clutch mechanism.

EDMUND S. SPINNEY.
